CLAIM

The ornamental design for combined applicator bottle and closure therefor, as shown and described.

DESCRIPTION

FIG. 1 is a right side view of a combined applicator bottle and closure therefor showing my new design;

FIG. 2 is a front view thereof;

FIG. 3 is a bottom view thereof;

FIG. 4 is a top view thereof;

FIG. 5 is a left side view thereof;

FIG. 6 is a right side view thereof, the closure removed, the bottle partially broken away for ease of illustration;

FIG. 7 is an exploded top view of the sprayer nozzle shown separately for ease of illustration;

FIG. 8 is a front view of the sprayer nozzle, shown separately for ease of illustration.

FIG.1

FIG.2
